UNITED STATES PATENT OFFICE.

THOMAS HEATH, OF ATTLEBORO, MASSACHUSETTS, ASSIGNOR TO C. H. EDEN COMPANY, OF ATTLEBORO, MASSACHUSETTS, A CORPORATION OF RHODE ISLAND.

DESIGN FOR A PATRIOTIC BADGE.

52,791.

Specification for Design.

Patented Dec. 24, 1918.

Application filed August 8, 1918. Serial No. 249,015. Term of patent 3½ years.

To all whom it may concern:

Be it known that I, THOMAS HEATH, a citizen of the United States, residing at the city of Attleboro, county of Bristol, Commonwealth of Massachusetts, have invented a new, original, and ornamental Design for a Patriotic Badge, of which the following is a specification, reference being had to the accompanying drawing, forming part thereof.

The figure is a face view of a patriotic badge, illustrating my new design.

I claim:

The ornamental design for a patriotic badge, as shown.

THOMAS HEATH.
